HAROLD L. MYERS, OF MORRISTOWN, NEW JERSEY

DISPLAY DEVICE

Application filed July 27, 1932. Serial No. 625,076.

The invention relates to display devices for merchandise and more particularly to that type of such devices which comprises a display member on which the merchandise is removably mounted, and a foldable easel for supporting said member in display position. The invention contemplates the provision of a display device of the indicated character which is simple in construction and of maximum stability in its display position and which is capable of being readily folded for storage and shipment. Another object is to provide a display device which is constructed and arranged for the ready attachment of the easel to the display member and for cooperation therewith in the supporting of the merchandise thereon. In addition, the invention proposes a novel arrangement of foldable sections extending lengthwise of the display member preferably at opposite edge portions thereof to increase the stability of said member and to cooperate therewith in the provision of additional means for supporting the merchandise. Other objects will appear from the description hereinafter, and the features of novelty will be pointed out in the claims.

In the accompanying drawings, which illustrate an example of the invention without defining its limits, Fig. 1 is a perspective view of the device in display position; Fig. 2 is a vertical section, on an enlarged scale, of said device in display position; Fig. 3 is a plan view thereof with parts broken away and in section; Fig. 4 is a rear view of the device in folded position for fastening the parts together; Fig. 5 is a corresponding front view; Fig. 6 is a rear view of the device in folded position for storage or shipment, and Fig. 7 is a fragmentary sectional view on an enlarged scale.

In its illustrated form, the display device comprises a front member 10 generally constructed of cardboard or the like in the form of a flat, rectangular card and provided with means whereby predetermined articles of merchandise are removably supported thereon; as shown in the drawings, this means comprises openings 11 of suitable size and shape to accommodate the articles of mer-

chandise for which the particular device is designed. As shown in Fig. 5, the openings 11 are arranged in vertically aligning outside rows *a* and vertically aligning inside rows *b*. The device further includes foldable sections, preferably located at the opposite longitudinal edges thereof for the purpose of providing backs for the outside rows *a* of openings 11, and which at the same time provide tubular members adapted to increase the rigidity of the front member 10 when the latter is in its display position. These foldable sections comprise outer flaps 12 foldably connected at 13 with the front member 10, and at 14 with rear members 15, the latter in turn being foldably connected at 16 with inner flaps 12a, which are foldably connected at 17 with tabs 18, pasted or otherwise secured to the rear face of the front member 10, as illustrated in Fig. 3. In the preferred construction, the flaps 12 and 12a, the rear members 15 and the tabs 18 all constitute integral continuations of each other and of the front member 10, and are foldable on score lines located at the points 13, 14, 16 and 17; obviously, however, the elements 12, 12a, 15 and 18 may be independent members foldably connected with each other in any conventional manner without changing the results obtained. In addition to their stiffening functions, the rear members 15 of the foldable sections, as previously stated, provide backs for the outer rows *a* of the openings 11, as will be more fully set forth hereinafter; preferably the rear members 15 include holes 19 located in registry with the openings 11 to enable the articles of merchandise to be easily removed from the latter at will.

The device further includes an easel whereby the front member 10 is supported in display position, which easel, in addition to its supporting function, provides backs for the inner rows *b* of the openings 11; the easel is in fixed connection with the aforesaid foldable sections and partakes of certain of the folding movements thereof, as will be set forth more clearly hereinafter. In its illustrated form the easel comprises an easel member 20, located in overlapping sur-

face engagement with the rear members 15 and secured thereto in any conventional manner, preferably by means of metallic staples 21. The aforesaid easel further includes a prop 22, foldably connected at 23 with the easel member 20, and at 24 with a collapsible base member 25, consisting of two sections foldably connected with each other at 26. The base member 25 is foldably connected at 27 with a flap 28 located in surface engagement with the easel member 20, and secured thereto by certain of the fastening devices 21 or their equivalent. A brace 29 is foldably connected at 30 with the flap 28, and in its operative position serves to maintain the easel, or more specifically, the prop 22 thereof, in its operative supporting position.

In the preferred arrangement, the easel member 20, prop 22, base member 25, flap 28 and brace 29 all constitute integral continuations of each other and are constructed from a single sheet of material such as cardboard or the like, the foldable connections 23, 24, 27 and 30 comprising customary score lines to facilitate the relative pivotal movements of the various elements; it will be obvious that some or all of the elements 20, 22, 25, 28 and 29 may comprise separate members foldably connected in any conventional manner to provide a corresponding arrangement. The brace 29 is preferably recessed or cut away, as indicated at 29a so as to be of a relatively lesser width than the width of the other associated elements which comprise the easel; the purpose of this special arrangement will be more fully described further on in the description. As shown in the drawings the easel member 20 is provided with holes 19a corresponding to the holes 19 and located in registry with the openings 11 of the rows b to facilitate the removal of the articles of merchandise from the last mentioned openings. In addition, the prop 22 includes apertures 31, which in the folded condition of the device shown in Fig. 4 are adapted to register with the staples or equivalent fastening devices 21 for the purpose to be more definitely pointed out hereinafter.

In practice, the openings 11 of the front member 10 are adapted to contain articles of merchandise, said openings 11 being dimensioned and shaped to receive the articles of merchandise 11a for which the device is designed, said articles 11a fitting said openings with sufficient snugness to be held thereby, as illustrated in Fig. 1. When thus utilized, the outer flaps 12 and the inner flaps 12a are folded or bent to positions perpendicular to the front member 10 so as to bring the rear members 15 into rearwardly spaced registry with the outer rows a of openings 11, and to coincidentally position the easel member 20 in rearwardly spaced registry

with the inner rows b of said openings, said rear members 15 and easel member 20 being parallel to the front member 10 and providing backs respectively for the openings 11 of the rows a and b, as is clearly indicated in Fig. 3 of the drawings. In this position of the parts, the foldable sections consisting of the flaps 12 and 12a and the rear members 15 which, in the illustrated example, extend lengthwise along the opposite vertical edges of the front member 10, also serve to stiffen the latter or to increase its rigidity against bending or collapse under the load imposed by the supply of articles of merchandise 11a contained in the openings 11. To support the device in its display position, the collapsible base member 25 is unfolded or extended to the position illustrated in Fig. 2, and the brace 29 is pivotally adjusted to seat its free edge in the angle formed by the base member 25 and the prop 22. In this way, the easel is given a triangular form in which the base member 25 provides a firm supporting base for the device, while the prop 22 serves to firmly fix the front member 10 in an upright inclined display position; unintentional collapse of the device is prevented by the brace 29, as will be clear from an inspection of Fig. 2.

In this condition of the device, the articles of merchandise 11a are attractively displayed for sale and in a position to be easily removed from the openings 11, as required; if any difficulty is encountered in removing the articles 11a from the openings 11, a finger or a suitable implement may be inserted through the holes 19 to easily force the articles 11a from the given openings 11.

To fold the device into a condition for storage or shipment, the brace 29 is swung upwardly on the fold 30 into surface engagement with the rear face of the easel 20, it being understood that the prop 22 will yield sufficiently to permit this adjustment of the brace 29; the base member 25 may then be collapsed inwardly on the folding line 26 so as to lie in a folded condition between the prop 22 and the flap 28 and brace 29, as will be clear. If the device contains no articles of merchandise 11a, the foldable sections consisting of the flaps 12, 12a and rear members 15 will occupy folded positions in which the rear members 15 lie in substantially surface engagement with the rear face of the front member 10, as illustrated in Fig. 6; if the device contains articles of merchandise 11a, the front member 10, the foldable sections above mentioned, and the easel member 20 will occupy the positions shown in Figs. 1, 2 and 3, while the easel will occupy the folded position shown in Fig. 6. In either case, the device is of compact, minimum dimensions, capable of being easily and readily stored or shipped.

In the manufacture of the device, the tabs 18 are secured by pasting or otherwise to the rear face of the front member 10, and the easel, consisting of the easel member 20, prop 22, base member 25, flap 28 and brace 29 is constructed as a separate element. To unite the easel with the associated elements of the display device, the front section 10 is first folded, for instance, to the left in Fig. 5, the flaps 12 and 12a swinging on the score lines 13, 14, 16 and 17 or their equivalent to permit this adjustment of said front member 10; this operation brings the rear members 15 and the flaps 12a and one of the flaps 12 into substantial surface engagement with the rear face of said front member 10, in the manner illustrated in Figs. 4 and 5. The easel member 20 is then properly positioned in overlapping relation and surface engagement with the collapsed rear members 15 with the base member 25 folded outwardly to the position as indicated in Fig. 4. The front face of the one rear section 15 is thus properly exposed through the one row *a* of openings 11 to permit a conventional stapling machine or its equivalent to act through said openings 11 for setting staples 21 or equivalent fastening devices in place in registry with the apertures 31 of the prop 22; the latter permit said staples 21 to be clinched in the customary manner or the equivalent fastening device to be acted on in a manner to securely fasten them in place. When this has been accomplished, the front member 10 is folded toward the right in the manner similar to that previously described to bring the parts to the position shown in Fig. 7, so as to expose the front surface of the other foldable section through the openings 11 of the other row *a*, and to permit a second row of staples 21 or equivalent fastening devices to be secured in place in registry with the other set of openings 31 of the prop 22. As clearly shown in Figs. 3 and 4, the reduced width of the brace 29 resulting from the recessed or cut out portions 29a is less than the distance between the staples 21 or equivalent fastening devices at the opposite edges of the easel member 20; the brace 29 accordingly presents no interference to the mechanical operation of stapling or its equivalent. As a result of this construction and arrangement, the staples 21, or their equivalent, may be easily and quickly placed in position, without the exercise of any particular care, and automatically will simply pass through the rear members 15 and the easel member 20, and at the bottom of the device may also extend through the flap 28. The easel is thus efficiently combined with the display section of the device so as to span or bridge the space between the foldable sections located

along opposite edges of the front member 10, and so as to provide backs for the inner rows *b* of the openings 11, as previously described.

The device is extremely simple in construction and in use supports a predetermined supply of articles of merchandise 11a in an attractive display position which, at the same time, renders such articles of merchandise easily accessible for removal and sale at will. The device consists essentially of but two elements, each capable of being constructed from individual sheets of material, such as cardboard, said two elements being capable of being combined with each other in a manner requiring no particular skill or supervision in its performance. It will, of course, be understood that the various foldable portions of the device may comprise independent elements pivotally connected with each other, in which case the score lines of the illustrated form of the invention may be replaced by other means, whereby said independent elements are pivotally connected with each other to produce the same results. In its display position, the device is of maximum rigidity and supports the merchandise in an efficient manner, even when the full supply for which the device is designed is included therein.

Various changes in the specific forms shown and described may be made within the scope of the claims without departing from the spirit of the invention.

I claim:

1. A display device of the kind described comprising a front member provided with parallel outer and inner rows of openings arranged in vertical alignment to removably receive predetermined articles of merchandise, outer flaps foldably connected with said front member along opposite vertical edges thereof, inner flaps foldably connected with said front member in spaced parallel relation to said outer flaps, rear members extending between and foldably connected with an inner and an outer flap and positioned thereby in spaced relation to said front member to constitute backs for the outer rows of openings and to form foldable sections along opposite vertical edges of said front member to increase the rigidity thereof, said flaps and rear members comprising integral continuations of each other and said front member, and a foldable easel connected with said rear members and arranged to be positioned therewith in spaced relation to said front member to form backs for the inner rows of openings, said easel supporting said front member in display position.

2. A display device of the kind described comprising a front member provided with openings arranged in groups to removably receive predetermined articles of merchan-

dise, flaps foldably connected with said front member, rear members foldably connected with said flaps and positioned thereby in spaced relation to said front member to form backs for predetermined groups of said openings, said flaps and rear members comprising integral continuations of each other and said front member, and a foldable easel connected with said rear members and positioned therewith in spaced relation to said front member to form backs for other predetermined groups of said openings, said easel supporting said front member in display position.

15 3. A display device of the kind described comprising a front member provided with openings arranged in groups to removably receive predetermined articles of merchandise, flaps foldably connected with said front member, rear members foldably connected with said flaps and positioned thereby in spaced relation to said front member to form backs for predetermined groups of said openings, and an easel connected with said rear members and positioned therewith in spaced relation to said front member to form backs for other predetermined groups of said openings, said easel supporting said front member in display position.

30 4. A display device of the kind described comprising a front member provided with openings arranged in parallel vertical rows for removably receiving predetermined articles of merchandise, foldable sections foldably connected with said front member in spaced relation to each other to provide spaced tubular members adapted to increase the rigidity of said front member and to provide backs for predetermined rows of said openings, and an easel connected with said foldable sections for supporting said front member in display position and movable with said foldable sections into spaced relation to said front member to provide backs for other predetermined rows of said openings.

35 5. A display device of the kind described comprising a front member provided with means for removably supporting articles of merchandise, an easel for supporting said front member in display position, and spaced foldable sections foldably connected with said front member to provide tubular members for stiffening said front member, said foldable sections extending into the supporting range of said easel in fixed connection therewith.

40 6. A display device of the kind described comprising a front member provided with openings for removably receiving predetermined articles of merchandise, foldable sections foldably connected with said front member in spaced parallel relation to increase the rigidity thereof and to provide

backs for some of said openings, an easel member engaging and bridging the space between said foldable sections to provide backs for others of said openings, a prop foldably connected with said easel member for supporting said front member in display position and provided with apertures, a collapsible base member foldably connected with said prop, a foldable brace comprising an integral extension of said base member for fixing the latter in an extended position and said prop in operative position, said brace being of reduced width throughout a portion of its length, and fastening devices in registry with certain of said openings and said apertures for securing said easel member to said foldable sections.

7. A display device of the kind described comprising a front member provided with openings for removably receiving predetermined articles of merchandise, an easel member adapted to provide backs for at least some of said openings, a prop foldably connected with said easel member for supporting said front member in display position and provided with apertures, fastening devices in registry with said last-mentioned openings and said apertures for securing said easel member in place and a brace foldably connected with said easel member for fixing said prop in operative position and recessed at its opposite longitudinal edges to a width less than the distance between opposed fastening devices.

8. A folded display device of the kind described comprising a front member provided with merchandise receiving openings, spaced rear members forming backs for certain of said openings, flaps foldably connecting said rear members with said front member whereby the latter and said rear members are foldable into substantial surface engagement with each other, a foldable easel extending between said rear members and overlapping the same to provide backs for others of said openings, said easel being provided with apertures, and fastening devices accessible through said last-mentioned openings and said apertures and extending only through said rear members and a predetermined part of said easel for securing the latter to said rear members.

9. A folded display device of the kind described comprising a front member provided with merchandise receiving openings, spaced rear members forming backs for certain of said openings, flaps foldably connecting said rear members with said front member whereby the latter and said rear members are foldable into substantial surface engagement with each other, an easel member extending between said rear members and overlapping the same to provide backs for others of said openings, a prop

pivotedly connected with said easel member and lying in folded relation thereto, said prop being provided with apertures, a collapsible base member foldably connected with said prop and said easel member and folded outwardly beyond the same, a brace pivotally connected with said easel member and lying in surface engagement therewith

and between said member and prop, said brace being recessed along its outer edges, and metal staples accessible through said last-mentioned openings and said apertures and extending only through said rear members and easel member at opposite sides of the recessed portions of said brace. ⁷⁰
